UNITED STATES PATENT OFFICE

2,652,406

METHOD FOR THE PREPARATION OF
LACTONES

Laurent Lucien Crabalona, Grasse, France, assignor to Societe Anonyme des Etablissements Roure-Bertrand Fils & Justin Dupont, Paris, France, a corporation of the French Republic

No Drawing. Application August 13, 1948, Serial No. 44,227. In France September 20, 1947

3 Claims. (Cl. 260—343)

1

Monocyclic lactones having more than 12 chain members in the lactone ring were studied at length by Kerschbaum (German Patent No. 449,217 of the 6th of March 1926 and Ber. Deutsch. Chem. Ges. 1927, vol. 60, pp. 902 ff.) who showed that they could not be obtained by the ordinary methods of esterification because such methods gave rise to polymers without interest.

The special procedure described by Kerschbaum consists in heating under particular conditions the silver salts of halogenated fatty acids in which the halogen atom is in at least the 12th position in relation to the carboxyl group. In this way three lactones having an odor of musk were prepared, the 1,15-pentadecanolide, the 1,16-hexadecanolide and the 1,16 hexadecene-7-olide (ambrotolide), but the yields obtained were not reported.

Since that time other methods have been worked out for the preparation of these lactones, particularly the following:

a. The oxidation of cyclic ketones (Ruzicka and Stoll Helv. Chim. Acta 1928, 11, 1159; cf. also French Patent No. 657,971 of the 23rd of July 1928).

b. The internal ring-closure of oxyacids in a highly diluted medium (French Patent No. 773,651 of the 3rd of September 1934 and Certificate of Addition No. 46,623 of the 19th of May 1934).

c. The depolymerization of the corresponding polyesters (French Patents No. 768,807 of the 28th of May 1934 and No. 796,410 of the 22nd of January 1936).

d. The treatment of certain halogenated fatty acids in an alkaline medium and in the presence of certain low boiling point solvents (French Patent No. 839,188 of the 11th of June 1938 of Hunsdacher, Erlbach and Vogt).

e. The heating of an ester of an oxyacid in the presence of a catalyst of the exchange of functional groups (French Patent No. 830,689 of the 13th of December 1937 and Certificate of Addition No. 49,302 of the 10th of March 1938) etc.

The practical operation of these methods presents various inconveniences such as extreme dilution, the use of high vacua, the need for using special apparatus, the use of uncommon reagents, extreme slowness of the reactions, decomposition of the products, etc. It should be added that the yields also are not always satisfactory and that the quality of the lactones obtained leaves something to be desired, which is a particularly

serious shortcoming in products intended for perfumery.

The process of the present invention is a process for the preparation of these lactones which is simple and rapid in operation; which uses standard apparatus and common reagents; and finally which gives these lactones with very great purity and a high yield.

This process is based on a reaction of internal double decomposition of certain esters in the presence of catalysts favoring the exchange of functional groups. A double decomposition reaction of this kind for the preparation of organic esters was proposed in United States of America Patent No. 1,860,092 of the 31st of October 1929 George Graves assignor to E. I. du Pont de Nemours and Co.

In this patent it is stated that an ester of composition $R^4-COO-R^3$ can be prepared by the interaction of two esters $R^1-COO-R^3$ and $R^4-COO-R^2$ in the presence of a catalyst of the exchange of radicals; R^1-COO and R^4-COO being the anions of carboxylic acids; R^2 and R^3 being alkyl radicals; the equilibrium equation is the following

The new process forming the subject of the present invention can better be understood by starting from this Equation 1.

Considering now a diester of special form and deriving from an omega-hydroxylated acid; this diester has the formula

in which R is a chain containing at least 11 carbon atoms. This radical R can be split into two parts R^3 or R^4 each representing an open chain containing at least 5 carbon atoms; the above ester can then be formulated as

In this form it presents a striking analogy with an equimolecular mixture of the esters

Experience has shown that in certain conditions which will be specified later, this body (i. e. the diester) behaves exactly like such a mixture in forming the lactone

3

and the ester $R^1-COO-R^2$ in accordance with the equilibrium equation

which, replacing once more R for R^3+R^4 , can be rewritten in the form

If R^1 and R^2 are radicals containing few carbon atoms, the ester $R^1-COO-R^2$ is very volatile, it escapes from the reaction zone, the equilibrium is disturbed and the Reaction II proceeds from left to right yielding the desired lactone.

Experience has also shown that the Reaction II can proceed in the same way if the carboxylic anion R^1-COO^- is replaced by a mineral anion AO^- able to form a very volatile ester with the alcohol R^2-OH ; in that case the equation becomes

or, what comes to the same thing

The present invention, the mechanism of which has just been explained, is thus essentially characterised by the decomposition, which can be regarded as an internal exchange of radicals, of a diester itself obtained by the combination of an omega-hydroxy-ester of the form

either with an organic acid R^1-COOH or with a mineral acid AOH , the radical R comprising at least 11 carbon atoms. This decomposition takes place under the action of heat with if necessary a reduction of pressure and in the presence of a standard catalyst of the exchange of radicals.

As can be seen from the above, one of the important features of the present invention lies in the choice of the organic acid R^1-COOH (or of the mineral acid AOH) and of the alcohol R^2-OH so that by virtue of the high volatility of the ester $R^1-COO-R^2$ (or AOR^2) the Reaction II can take place immediately and at a temperature low enough to enable an excellent yield of monomeric lactone to be obtained. Thanks to the mildness of the reagents used and the conditions of preparation, the lactones obtained by this process are chemically and olfactorily very pure.

No reaction of this type has been mentioned in the literature and this new reaction is fundamental to the present invention. The only known reaction which could in certain directions be regarded as approaching that which has just been described is the decomposition mentioned above of an ester of an oxyacid $H.O.R.COO-R'$ with formation of a lactone

and an alcohol $R'OH$ (French Patent No. 830,689); but to make clear the essential differences between the two processes, it suffices to point out that:

a. The French Patent No. 830,689 is concerned with an exchange reaction between an alcohol and an ester and not between two esters, or, what comes to the same thing, in the patent there is formation of an alcohol as the second product while in the process herein claimed there is formation of an ester as the second product.

4

b. The French Patent No. 830,689 categorically states that for the reaction to succeed, it is essential that the second product of the reaction—which is an alcohol—should be such that it is not easily eliminated from the reaction mixture and has a boiling point above 100° C. at a pressure of 2 mm. of mercury.

In the new process here described, exactly the opposite applies; the second body formed—which is here an ester—must be very volatile and distil over at a temperature substantially lower than does the lactone; in practice as will be seen from the examples given later, the ester formed at the same time as the lactone is gaseous under the conditions of the reaction and its elimination is therefore instantaneous.

c. In the French Patent No. 830,689 in order that the exchange reaction may take place it is essential to carry the heterogeneous mixture to a high temperature and to eliminate the lactone from the reaction zone when and as it is formed, utilising the well-known property of polyols of carrying off less volatile bodies with their vapors; this is the phenomenon of glycolic co-distillation which has been the subject of many investigations (of particularly Sabetay Ann. Chimie Analytique 1939, vol. 21, p. 173, and 1940, vol. 22, p. 217).

In the process here claimed there is nothing comparable; there is no possibility of the lactone being carried off by the ester formed and, the equilibrium being rapidly disturbed by the volatilization of the ester, the formation of the lactone takes place very easily at a much lower temperature. It suffices thereafter to raise the temperature slightly to distil off the lactone under vacuum.

It is hardly necessary to point out the resulting technical advantages, particularly from the point of view of the purity of the lactones obtained.

It is to be understood that the radical R (which for convenience in discussion was previously thought of as split into two sections R^3+R^4) comprises at least 11 carbon atoms in open chain and may reach a substantially higher figure; this radical R can be a straight or branched chain; it may be homogeneous, that is to say comprise only saturated radicals consisting only of carbon and hydrogen or it may be heterogeneous that is to say comprise one or more double or triple bonds, one or more hetero-atoms (such as oxygen, nitrogen, sulphur, etc.) whatever may be the internal linking of these different radicals or groups.

The radical R^1 of the acid R^1-COOH which esterifies the OH of the hydroxyester can be hydrogen or a simple radical containing a low number of carbon atoms; thus the acid R^1-COOH will be for example formic acid, acetic acid, or one of their immediate homologues chosen so as to obtain after the reaction a very volatile ester $R^1-COO-R^2$.

Similarly the mineral radical AO^- corresponding to the mineral acid AOH , also able to esterify the OH of the hydroxy-ester will be chosen among the mineral acid radicals giving with the alcohol R^2-OH a very volatile ester AOR^2 ; by way of an indicative and not limitative example, boric, carbonic and sulphuric acids may be mentioned.

Finally the alcohol R^2-OH which esterifies the acidity of the omega-hydroxy acid $H.O.R.COOH$ will preferably be chosen among the lower alcohols, that is to say among methyl, ethyl, propyl, butyl, etc. alcohols, always with a view to obtaining, along with the desired lactone, as volatile as

possible an ester $R^1-COO-R^2$ (or AOR^2); in other words R^2 is a lower alkyl group.

As catalyst in this reaction of exchange of functional groups which is at the basis of the process here claimed, a body known for its properties of catalyzing the exchange of radicals will be used; without the list being intended to be limitative, the two following groups are particularly recommended: the alkaline or earth alkaline derivatives of mono- or polyvalent alcohols or phenols; and more or less ionized bodies with an acid reaction, such as sulphuric or phosphoric acid, organic acids, arylsulphonic acids, etc.; it will be understood that the proportion of catalyst cannot be laid down in advance and will be determined in each case according to the activity of the catalyst and the speed of reaction it is desired to obtain; in a more general way, the present invention is not tied to the use of a particular catalyst.

The temperature and pressure will be chosen at the discretion of the operator according to the nature of the constituents of the reaction and their volatility.

The examples which follow will enable the possibilities of practising the invention to be appreciated; it will be understood that the examples are only given by way of indication; they in no way limit the invention which has been described above.

Example 1

21 grams of methyl-16-acetoxyhexadecanoate were heated at 220-230° C. (temperature of the heating bath) under a pressure of 3 mm. of mercury, in the presence of sodium methylate. In an hour and a half 11.6 gms. of distillate were collected in the form of a colorless oil which crystallized in the receiver. Yield 71.3 per cent of the theoretical as lactone. This distillate had the following properties; distilled completely between 127 and 129° C. under a pressure of 2.5 mm. of mercury, solidification point +33.5° C., density $d_4^{37}=0.9324$, refractive index $n_D^{34}=1.4662$, saponification value 221.5.

Within the limits of experimental error, these constants are those of pure 1-16-hexadecanolide, given in the literature (Helv. Chim. Acta, vol. 11, 1171 (1928)).

Example 2

25.7 grams of butyl-16-hydroxyhexadecanoate were converted into boric ester by means of 1.56 gm. of boric acid. The water formed was driven off, the diester heated under a reduced pressure of 3 mm. of mercury in the presence of sodium methylate. With the heating bath at 180-190° C. a very mobile colorless liquid distilled off. This was collected; it weighed 5.05 gm. This was butyl borate, for it distilled completely at 122-124° C. under a pressure of 24 mm. of mercury, and at 97-99° C. under a pressure of 6 mm. of mercury; index of refraction $n_D^{17}=1.4120$; water hydrolyzed it into butanol and boric acid.

Heating under a vacuum was continued and when the temperature of the heating bath reached 230-240° C., 13.1 grams of distillate were collected in 2 hours, the constants of which were practically identical with those of the lactone obtained in Example 1.

Yield 64.8 per cent of theoretical.

Example 3

23.2 gms. of methyl-14-hydroxy-tetradecanoate were converted into boric ester by treatment with butyl borate. The butanol formed was driven

off, then the excess of butyl borate; sodium butylate was introduced and heating was effected under a reduced pressure of 3 mm. of mercury. With the heating bath at 230-240° C., 12.5 gms. of distillate were collected during one hour.

The distillate was a colorless oil having an odor of musk, with the following characteristics:

Distilled completely between 110° and 112° C. at 2 mm.

Solidification point, 27° C.

Index of refraction n_D^{28} , 1.4701

Density d_4^{30} , 0.9530

Saponification value, 246.7

Within the limits of experimental error, these constants are those of 1-14-tetradecanolide given in the literature (Helv. Chim. Acta, vol. 11, 1171 (1928)).

Yield 61 per cent of the theoretical.

Example 4

20 grams of methyl-2-hydroxy-dodecanoate were converted into boric ester by treatment with boric acid.

The diester was heated to 220-230° C. under a reduced pressure of 3 mm. of mercury, in the presence of sodium methylate. In 80 minutes 10.1 gms. of distillate were collected.

This was a colorless oil, sprinkled with small shining white crystals. Its odor was disagreeable; it recalled that of a burnt-out candle and of a mouldy cork bung, with a slight musty smell of mint.

Under fractional distillation, at 2 mm. of mercury, these 10.1 gms., yielded between 83 and 85° C., 8.5 gms. of a colorless oil having the same odor, and 1.45 gm. of residue.

The distilled oil had the following characteristics:

Density d_4^{15} 0.9800

Refractive index n_D^{17} 1.4715

Saponification value 280.7

Within the limits of experimental error these constants are those of 1-12-dodecanolide given in the literature (Helv. Chim. Acta, vol. 18, 1120 (1935) Stoll and Rouvé).

The yield was 49.3 per cent of the theoretical while Stoll and Rouvé obtained only 16 per cent by the method of great dilution.

The residue from the fractionation, twice recrystallized from alcohol, melted at 104° C. and had a saponification value of 282.8. This is the theoretical value for the dilactone for which Stoll and Rouvé give a melting point of 101°.

Example 5

23.7 gms. of methyl-1-acetoxy-3-oxa-15-tetradecacarboante heated to 220-230° C. under a reduced pressure of 3 mm. of mercury, in the presence of sodium methylate, yielded 13.05 gms. of distillate in a period of 70 minutes. This distillate was a colorless oil, having an odor of musk, distilling completely between 110° and 112° C. at a pressure of 2.5 mm. of mercury. It had the following constants:

Solidification point °C. +12.5

Density d_4^{17} 0.9950

Refractive index n_D^{17} 1.4702

Molecular refraction R_D found 67.86

Calculated for $C_{14}H_{26}O_3$ 67.95

Saponification value 235.2

Calculated for $C_{14}H_{26}O_3$ 231.4

70 75

Yield as cyclo-1,14-dioxa-tetradeca-2-carbanone

68 percent of the theoretical.

Example 6

28.8 gms. of methyl-1-hydroxy-4-oxa-16-pentadecacarboante were treated with boric acid.

The resulting diester was heated at 220-230° C. under a reduced pressure of 3 mm. of mercury, in the presence of sodium methylate. 18.45 gms. of pure lactone were obtained, a yield of 72 per cent of the theoretical. It was a colorless liquid with an odor of amber and musk, which had the following constants:

Boiling point at 2 mm. of mercury °C 113-115

Refractive index n_D^{20} 1.4683

Density d_4^{20} 0.9853

Molecular refraction R_D found 72.25

Calculated for $C_{15}H_{28}O' O' O'$ 72.45

Saponification value found 221.2

Calculated for cyclo-1-14-dioxa-penta-deca-2-carbanone

Example 7

13.80 gms. of methyl-16-acetoxy-7-hexadecenoate were heated at 220-250° under a reduced pressure of 3 mm. of mercury, in the presence of sodium methylate. In 1 1/4 hours, 8.37 gms. of distillate were collected in the form of a colorless oil having a strong odor of musk.

This distillate had the following characteristics:

Redistilled at 3 mm. of mercury, it distilled over completely between 142 and 144° C.

Density d_4^{20} 0.9577

Refractive index n_D^{20} 1.4816

Molecular refraction R_D found 74.96

Calculated for $C_{16}H_{28}O_2$ (with a double bond between two atoms of carbon, one oxygen atom being linked with a carbon atom through a double bond and the other atom of oxygen being linked with a carbon atom through a single bond) 75.07

Saponification value 224.0

Calculated for $C_{16}H_{28}O_2$ 222.2

Iodine value (theory 100.7) 98.5

Within the limits of experimental error, these constants are those of 7-hexadecene 1,16 olide (ambretolide) given in the literature (Helv. Chim. Acta, vol. 17, 1612 (1934)).

The yield of the operation in monolactone was 78.4 per cent of the theoretical.

As has already been mentioned, these examples are described only by way of indication and not as limiting the invention; in particular the substances mentioned could, each in its category, be replaced by others having analogous properties; similarly the numerical particulars given could be varied within wide limits without departing from the scope of the invention.

What I claim is:

1. A method for producing substantially pure monocyclic lactones including at least 12 carbon atoms in the lactone ring, comprising providing at raised temperature and under reduced pressure, in the presence of a catalyst, the cyclization of a diester

10 wherein n is an integer from 10 to 15 inclusive, R_2 an alkyl radical selected from the group including methyl, ethyl, propyl and butyl, and A the radical of an acid adapted to produce an ester of high volatility with the said alkyl radical, said reaction producing a lactone

and an ester $A-\text{O}-R_2$ much more volatile than the lactone, allowing said ester to evolve immediately in gaseous form and recovering the pure liquid lactone.

2. A method for producing substantially pure monocyclic lactones including at least 12 carbon atoms in the lactone ring, comprising providing at raised temperature and under reduced pressure, in the presence of a catalyst, the cyclization of a diester

wherein m is an integer from 0 to 3 inclusive and n is an integer from 10 to 15 inclusive, R_2 an alkyl radical selected from the group including methyl, ethyl, propyl and butyl, said reaction producing a lactone

and an ester $H(\text{CH}_2)_m-\text{COOR}_2$ much more volatile than the lactone, allowing said ester to evolve immediately in gaseous form and recovering the pure liquid lactone.

3. A method for producing substantially pure monocyclic lactones including at least 12 carbon atoms in the lactone ring, consisting in providing at raised temperature and under reduced pressure, in the presence of a catalyst, the cyclization of a diester $A-\text{O}(\text{CH}_2)_n-\text{COOR}_2$, wherein n is an integer from 10 to 15 inclusive, R_2 an alkyl radical selected from the group including methyl, ethyl, propyl and butyl and A the radical of an acid selected from the group consisting of boric, carbonic and sulfuric acids, said reaction producing a lactone

and an ester $A-\text{O}-R_2$ much more volatile than the lactone, allowing said ester to evolve immediately in gaseous form and recovering the pure liquid lactone.

LAURENT LUCIEN CRABALONA.
